UNITED STATES PATENT OFFICE

126,970

DESIGN FOR A COMBINATION WATER BOTTLE AND ICE BAG OR SIMILAR ARTICLE

Raymond W. Albright, Akron, Ohio, assigner to American Anode Inc., Akron, Ohio, a corporation of Delaware

Application October 31, 1940, Serial No. 96,241

Term of patent 14 years

To all whom it may concern:

Be it known that I, Raymond W. Albright, a citizen of the United States, residing at Akron, in the county of Summit and State of Ohio, have invented a new, original, and ornamental Design for a Combination Water Bottle and Ice Bag or Similar Article, of which the following is a specification, reference being had to the accompanying drawing, forming a part thereof.

In the drawing,

Fig. 1 is a front elevational view of a combination water bottle and ice bag or similar article embodying my new design;

Fig. 2 is a vertical section taken on line 2—2 of Fig. 1.

The back of the bag or similar article is substantially plain.

The dominant features of the design are shown in solid lines and the subordinate features are shown in broken lines.

I claim:

The ornamental design for a combination water bottle and ice bag or similar article, as shown and described.

RAYMOND W. ALBRIGHT.
